S. J. SILL.

MACHINE FOR DISCONNECTING THE SECTIONS OF HOSE FORMING MANDRELS.

APPLICATION FILED JAN. 2, 1913.

1,123,409.

Patented Jan. 5, 1915.

UNITED STATES PATENT OFFICE.

SAMUEL J. SILL, OF BUFFALO, NEW YORK, ASSIGNOR OF ONE-HALF TO HERBERT H. HEWITT, OF BUFFALO, NEW YORK.

MACHINE FOR DISCONNECTING THE SECTIONS OF HOSE-FORMING MANDRELS.

1,123,409.

Specification of Letters Patent.

Patented Jan. 5, 1915.

Application filed January 2, 1913. Serial No. 739,879.

To all whom it may concern:

Be it known that I, SAMUEL J. SILL, a citizen of the United States, and a resident of Buffalo, county of Erie, and State of New York, have invented certain new and useful Improvements in Machines for Disconnecting the Sections of Hose-Forming Mandrels, of which the following is a full, clear, and exact description.

10 The invention seeks to provide a simple and effective construction by which the sections of hose-forming mandrels may be readily disconnected, and consists in the features of improvement hereinafter set forth, 15 illustrated in its preferred form in the accompanying drawings, and more particularly pointed out in the appended claims.

In the drawings,—Figure 1 is a plan view of the improved machine; Fig. 2 is a longitudinal section; and Fig. 3 is a face view of one of the chuck heads.

The improved machine comprises a bed plate 1 mounted at its ends upon suitable supporting legs 2. In the construction shown, the machine is driven from an electric motor 3, which is mounted on one end of the bed plate, and the shaft 4 of which is provided with a drive pinion 5. The pinion 5 meshes with a gear 6 upon one end of a short shaft 7, and which shaft is journaled in the outer end portion of the U-shaped bracket 8 which is secured to the bed plate. A second short shaft 9 is journaled in the other portion of the bracket 8 and is arranged in line with the shaft 7. The shafts 7 and 9 are adapted to be connected and disconnected by a clutch 10 of any suitable construction. In the construction shown the clutch shoes are operated by a sliding cone 11 on the shaft 9, which acts upon a pair of arms 11'. The cone is shifted by a hand lever 12, which is pivoted to a stud 13 on the bracket 8 and is provided with a yoke-shaped portion extending about the clutch cone 11. Pins 14 on the yoke-shaped portion of the lever extend between annular flanges 15 on the cone. By shifting the lever, the shaft 9 may be connected to the electric motor or other suitable source of power, and disconnected therefrom.

A standard 16 is mounted at the opposite end of the base plate 1, and is provided with a bearing portion 17, through which extends a shaft 18, the latter being arranged in line with the shaft 9 at the opposite end of the

bed plate. The shaft 18 is longitudinally movable through the bearing 17, but is held against rotation therein, preferably by means of a key 19. This shaft is shifted by a lever 20, which is connected by a pivot bolt 21 to a part 22 extending outwardly from the bearing 17. The lever is provided with a yoke-shaped portion which extends over the outer end of the shaft 18 and over a grooved collar or sleeve 23 mounted on the shaft. Pins 24 on the yoke portion of the lever engage the grooved collar, so that the shaft may be shifted longitudinally by the lever.

The inner ends of the shafts 9 and 18 are provided with chuck heads 25 and 26, and these heads are provided with axial recesses 27 on their inner faces. The recesses 27 are provided with flattened side walls which are arranged to engage the correspondingly shaped end portions of the sections of a hose-forming mandrel. This mandrel comprises a main body 28 having a slightly enlarged portion 29 at one end, with a terminal collar 30 surrounding the enlarged portion. At its opposite end, the mandrel is provided with a screw-threaded stem 31 of reduced diameter. A sleeve 32 is threaded on the stem into engagement with the end of the main portion of the mandrel. This sleeve corresponds in size to the enlarged portion 29 of the mandrel and has a terminal collar 33 corresponding to the collar 30. The collars 30 and 33 are provided with flattened faces at their end portions and are adapted to fit within the recesses 27 of the chuck heads 25 and 26.

This mandrel is employed for forming and vulcanizing hose sections having enlarged ends, and such as are used in railway air-brake systems. As indicated in the drawings, the enlarged ends of the hose section 34 extend over the portion 29 of the mandrel and the sleeve 32, and abut against the terminal collars 30 and 33. After the hose is completed, the mandrel, with the hose thereon, is placed in position between the chuck heads 25 and 26, with the flattened end portions thereof extending within the correspondingly shaped recesses 27 of the chuck heads. The mandrel is securely held in position by a spring 35, which is coiled about the shaft 18 and extends between the bearing 17 and the head 26 thereon. This spring presses the longitudinally movable

shaft 18 and parts carried thereby inwardly toward the relatively fixed chuck-head 25, so that the mandrel is securely held between the heads. In placing the mandrel in position, the shaft 18 and chuck head 26 thereon are shifted outwardly against the tension of the spring 35 by the lever 20. After the mandrel is in position, the lever 12 is shifted to connect the shafts 7 and 9 by means of the clutch 10. The shaft 9 is then rotated to revolve one of the sections of the mandrel, while the other section is held against movement by the non-rotatable shaft 18. The sleeve 32 is thus unscrewed from the stem 31, and as it is unscrewed, the chuck head 26 is moved outwardly against the pressure of the spring 35. The sections of the mandrel are thus readily, easily and rapidly disconnected to permit the removal of the hose section without injury thereto.

While the primary object of the invention is the disconnecting of the mandrel sections to permit the removal of the finished hose, the machine is adapted for other purposes, such as wrapping the mandrel with the hose thereon in cloths preparatory to the vulcanizing operation. The machine may be readily adapted to this operation by permitting the rotation of the longitudinally movable shaft 18.

It is obvious that changes may be made in the details set forth without departure from the essentials of the invention as defined in the claims.

35 I claim as my invention:

1. In a machine of the class described, the combination with a bed plate having standards thereon, of a revolute shaft journaled on one of said standards, clutch-controlled drive mechanism for said shaft, a longitudinally movable shaft mounted in the other

of said standards, a spring for pressing said latter shaft inwardly, a collar on the outer end of said second shaft, and a hand lever engaging said collar for shifting said shaft against the tension of said spring, said shafts having chuck heads on their inner ends provided with recesses for engaging the squared ends of a mandrel, substantially as described. 15

2. In a machine of the class described, the combination with a bed plate having standards thereon, of a revolute shaft journaled on one of said standards, clutch-controlled drive mechanism for said shaft, a longitudinally movable shaft mounted in the other of said standards and held against rotation therein, a collar on said second shaft, a hand lever engaging said collar for shifting said longitudinally movable shaft, 60 and chuck heads on the inner ends of said shafts having axial recesses for engaging the squared ends of a mandrel, substantially as described. 65

3. In a machine of the class described, the combination with a bed plate having standards thereon, of a revolute shaft journaled on one of said standards, clutch-controlled drive mechanism for said shaft, a longitudinally movable shaft mounted in the other of said standards and keyed thereto, a spring for pressing said latter shaft inwardly, and a hand lever for shifting said longitudinally movable shaft against the tension of said spring, said shafts having chuck heads on 70 their inner ends provided with axial recesses for engaging the squared ends of a mandrel, substantially as described. 75

SAMUEL J. SILL.
